[57] CLAIM

The ornamental design of an animal ear fob, showing my design.

DESCRIPTION

FIG. 1 is a top plan view of an animal ear fob or similar article showing my new design;

FIG. 2 is a left side elevational view thereof;

FIG. 3 is a rear elevational view thereof;

FIG. 4 is a right side elevational view thereof;

FIG. 5 is a bottom plan view thereof;

FIG. 6 is a front elevational view thereof; and,

FIG. 7 is a perspective view thereof, showing a key ring and chain for attachment thereto.
The broken line showing of a key ring and chain, in FIG. 7, is for illustrative purposes only and forms no part of the claimed design.
